UNITED STATES PATENT OFFICE.

HERMAN F. C. SOELLNER, OF NEW YORK, N. Y.

DESIGN FOR AN ADVERTISING DEVICE.

No. 38,720.

Specification for Design.

Patented Aug. 6, 1907.

Application filed May 24, 1907. Serial No. 375,555. Term of patent 14 years.

To all whom it may concern:

Be it known that I, HERMAN F. C. SOELLNER, a citizen of the United States, and a resident of the city of New York, (borough of Brooklyn,) in the county of Kings and State of New York, have invented a new, original, and ornamental Design for an Advertising Device, reference being had to the accompanying drawing, in which the figure is a perspective view of an advertising device, showing my design.

I claim:

The ornamental design for an advertising device, as shown.

HERMAN F. C. SOELLNER.
